UNITED STATES PATENT OFFICE.

FREDERICK F. GAINES, OF SAVANNAH, GEORGIA.

CAR-COUPLER-POSITIONING DEVICE.

Application filed March 11, 1920. Serial No. 364,953.

To all whom it may concern:

Be it known that I, FREDERICK F. GAINES, a citizen of the United States, and resident of the city of Savannah, in the county of 5 Chatham, State of Georgia, have invented certain new and useful Improvements in Car-Coupler-Positioning Devices, of which the following is a specification.

The object of my invention is to provide 10 a safe mechanical method of positioning or adjusting car couplers, so that cars can be readily coupled in shifting in railway yards, and about industrial plants.

Couplers have approximately three inches 15 lateral motion on carrier irons, and in some instances, considerably more where end sills are battered by wear, and it is the trainmen's practice to kick the couplers into line or go in between the cars, and line up 20 couplers by hand; either method is prolific cause of loss of life or serious injury.

A further object of my invention is to provide a simple but effective organization of elements of such construction that they 25 will withstand the rough usage incident to positioning couplers: and with this and other objects in view my invention consists of the parts and combination of parts as will be hereinafter more fully set forth.

30 In the drawing:

Figure 1 is an end elevation of a car broken away on which my improved positioning device is mounted.

Figure 2 is a top plan view of the same. 35 Figure 3 is an enlarged detail sectional view of the line 3—3 Figure 1.

The reference numeral 1 designates a sill of any suitable construction upon which is mounted the striking iron 2 in which the 40 carry iron 3 is swingingly mounted by the links 4. The coupler 5 is mounted upon the carry iron 3 as shown.

My improved positioning device includes a bell crank lever consisting of the arms 6 45 and 7 which are independently pivotedly mounted on a journal 8 which is suitably secured to the end sill, there being a washer 9 interposed between the end sill and the inner end of the arm 7 of the bell crank lever as clearly shown in Figure 3. The 50 arms 6 and 7 are suitably secured on the pin 8 by any desirable means such as the washer and cotter pin 10. The arm 7 is provided with a lug 11 near its outer end upon which is pivotedly mounted the hand latch 12 which is normally spaced from the hand

grip 13 by the spring 14. To the inner end of the hand latch 12 I pivotally secure the outer end of a bolt 15, the inner end of the bolt being slidably confined with a strap or 60 housing 16. The upper end of the arm 6 is provided with a recess 17 within which the inner end of the bolt 15 is adapted to be projected when the hand latch 12 is moved toward the hand grip 13, as shown in Figure 65 3, thereby rigidly locking the arms 6 and 7 together for cooperative movement for positioning the coupler.

A link 18 is pivotally secured to the carry iron 3 and to the lower end of the arm 6 70 of the bell crank lever.

A suitable loop strap 19, is positioned on the end sill under which the arm 7 of the bell crank lever is slidably confined.

When the parts are in the position shown 75 in Figure 1 the coupler and the carry iron are free to swing to accommodate service movements of the coupler without imparting any movement to the lever 7 so that it is very easy for the trainmen to grasp the 80 lever 7 without liability of being injured by a whipping action of the lever. When it is desired to position the coupler the hand clasp 12 is moved thereby projecting the inner end of the bolt 15 within the recess 85 17 thus locking the arms 6 and 7 of the bell crank lever rigidly together, so that if it is desired to position the coupler to the left the arm 7 is pushed downwardly thereby, through the arm 6 and link 18, throwing the 90 carry iron and the coupler toward the left. If it is desired to position the coupler toward the right the arm 7 is pulled upwardly.

While I have shown the bell crank lever and link 18 as connected to a carry iron it 95 will of course be understood that the link may be connected directly to the coupler, therefore, it will be understood that such a change can be made without departing from the scope of the appended claims. It will 100 also be understood that other changes may be made in the details of construction without departing from the scope of the appended claims.

What I claim is:

1. In a car coupler positioning device, the combination with a coupler, of a bell crank lever the arms of which have a flexible connection at their juncture, whereby one of said arms may move with the coupler in 110 service movements, and a latch mounted on one of said arms and adapted to engage

the other of said arms and lock the arms together and a connection between the coupler and the bell crank lever, whereby the coupler may be positioned by movement of the bell crank lever.

2. In a car coupler positioning device the combination with a car coupler, and a swinging carry iron for the coupler, of a bell crank lever the arms of which have a flexible joint at their juncture, a link connecting one of said arms with the carry iron, a latch on the other of said arms whereby the arms of the bell crank lever may be rigidly connected for positioning a coupler.

15 3. In a car coupler positioning device, the combination with the coupler and a swinging carry iron for the same, a bell crank lever the arms of which have a flexible joint at their juncture, a link connecting one of 20 said arms with the swinging carry iron, a latch mounted on the other of said arms to connect said arms rigidly together, and means for limiting the movement of the bell crank lever.

25 4. In a car coupler positioning device, the combination with a car coupler, of a swinging carry iron for the coupler, of a bell crank lever, the arms of which have a flexible joint at their juncture, a link connecting 30 one of said arms with the carry iron,

and means whereby the arms of the bell crank lever may be rigidly connected for positioning the coupler.

5. In a car coupler positioning device, the combination with a car coupler, of a swinging carry iron for the coupler, of a bell crank lever, the arms of which have a flexible joint at their juncture, means operatively connecting said bell crank lever with the carry iron, and means whereby the arms of the bell crank may be rigidly connected for positioning the coupler.

10 6. A car coupler positioning device, the combination with a car coupler, a swinging carry iron for the coupler, a bell crank lever, the arms of which have a flexible joint at their juncture, means for rigidly connecting said arms for joint action, and means operatively connecting the bell crank lever with the coupler.

15 7. In a car coupler positioning device, the combination with a car coupler, a bell crank lever, the arms of which have a flexible joint at their juncture, means for rigidly connecting said arms for joint action, and means operatively connecting the bell crank lever with the coupler.

20 In testimony whereof I affix my signature.

FREDERICK F. GAINES.
